(57) **CLAIM**

The ornamental design for a protective boat fender, as shown and described.

DESCRIPTION

FIG. 1 is a perspective view of a front of a protective boat fender, showing our new design;

FIG. 2 is a front view of the protective boat fender, showing our new design;

FIG. 3 is a back view of the protective boat fender, showing our new design;

FIG. 4 is a side view of the protective boat fender, showing our new design;

FIG. 5 is a side view of the protective boat fender, showing our new design;

FIG. 6 is a top view of the protective boat fender, showing our new design;

FIG. 7 is a bottom view of the protective boat fender, showing our new design;

FIG. 8 is a perspective view of a back of the protective boat fender, showing our new design; and,

FIG. 9 is a perspective view of an interior portion of the front of the protective boat fender, showing our new design.

The broken line depiction of a portion of the protective boat fender is included for the purpose of illustrating portions of the article and forms no part of the claimed design. The line depiction formed of a combination of dots and dashes of a portion of the protective boat fender is included for the purpose of illustrating portions of the article and forms no part of the claimed design.

1 Claim, 7 Drawing Sheets
